UNITED STATES PATENT OFFICE

2,563,143

POWER LIFT

Frank W. Wells, Pasadena, Calif., and Joseph T. Kulhavy, Rock Island, Ill., assignors to J. I. Case Company, Racine, Wis., a corporation of Wisconsin

Original application February 27, 1942, Serial No. 432,670. Divided and this application October 4, 1947, Serial No. 777,993

5 Claims. (Cl. 74—104)

1

The present invention relates to power lift apparatus and particularly to such apparatus as is adapted for application to tractors. This application is a division of a co-pending application, Serial No. 432,670, filed Feb. 27, 1942, and allowed April 9, 1947, now Patent No. 2,430,197.

An object of the invention is to generally improve the construction and operation of devices of this class. More particularly the invention relates to power lifts having arms which are actuated by fluid pressure and a further object of the invention is to avoid binding and excessive friction and wear in such rams and connected parts thereof.

A further object of the invention is to provide expedients for the accomplishment of the novel objects.

Further objects and advantages of the invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention as herein expressed. In the annexed drawing.

The single figure is a vertical sectional view of an illustrative embodiment of the invention.

As seen in the drawing, the invention comprises a casing or housing 5 which may be bolted or otherwise fixed on a tractor (not shown) in any convenient location to become a part thereof. Housing 5 serves to enclose the mechanism of the power lift proper and also as a reservoir for fluid. A shaft 6 which may be, for example, a power take-off shaft extending from the tractor in any convenient or well-known location, traverses housing 5 and is supported therein in anti-friction or other suitable bearings, it being desirable to locate housing 5 at such a point on the tractor that one of the well-known externally projecting power shafts commonly provided will pass through the housing 5 to serve as shaft 6. Shaft 6 actuates a pump unit generally designated as 9 which forces fluid from reservoir 5, when desired, into a ram cylinder 10 for accomplishing the usual purpose of a power lift, the fluid returning to reservoir 5 through an outlet valve generally designated as 11 when it is desired to lower the implements or objects connected with the lift. In the event that excessive pressure is developed for any reason by the action of pump 9, this is relieved by a relief valve generally designated as 12 and control

2

means generally designated as 13 operate to start and stop the actuation of pump 9 by shaft 6 and also to actuate outlet valve 11, control means 13 being adapted to automatically return to a neutral position whenever released, whereupon pump 9 stops and any implement connected with the power lift remains in status quo.

Ram cylinder 10 has a piston therein generally designated as 100 having a rod 101 extending upwardly through a suitable oil retainer of any well-known type 102. A head 103 is fixed to rod 101 and extends to one side where it is fixed with a guide rod 104, slidably in a guide portion 105 in the present instance forming part of housing 5. In this manner piston 100 is definitely guided independently of cylinder 10 so that any side thrust reaction occasioned by implements connected to be lifted or the like is taken by guide rod 104 rather than the walls of cylinder 10. Undue wear of the cylinder is thereby eliminated.

To minimize such side thrust, a connection to elements to be lifted is provided in the present instance in the form of a rock shaft 106 journaled in a suitable bearing or support 107 fixed with the tractor. Any well-known connection from rock shaft 106 to the various implements which it is desired to lift may be provided as will readily be understood by one skilled in the art. Rock shaft 106 has a bifurcated arm 108 extending to a region above piston rod 101 at which point it is pivotally connected with a thrust block 109 by a pin or the like 110. Thrust block 109 is pivotally connected as by a pin 111 with a bifurcated or suitable guide arm 112 pivoted at 113 in the present instance to above mentioned bearing 107. Thrust block 109 has a face 114 preferably at right angles to piston rod 101 and head 103 is provided with an anti-friction abutment, for example, a roller 115 in contact with face 114.

In the present arrangement, pivots 110 and 111 are disposed in a plane parallel to rod 101. Rock shaft 106 and pivot 113 are also disposed in a plane parallel to shaft 101, arm 108 and guide arm 112 being of equal length. Consequently, during swinging movement of arm 108 and guide arm 112, block 109 will in all positions remain parallel to rod 101. Therefore, since face 114 is at substantially right angles to rod 101, the reaction on rod 101 will always be axial to the rod and no side thrust will be developed by the rod 101 against block 109. Any side thrust developed by friction roller 115 is taken up by guide rod 104. Other arrangements which will insure that face 114 will remain perpendicular to rod 101 are

contemplated as within the scope of the invention.

Cylinder 10 may be secured in housing 5 in any suitable or desired manner, in the present instance the cylinder being seated against a gasket 138 in a counter-bore 139 by means of a nut 140 threaded in a boss 141 in housing 5. Nut 140 carries above mentioned oil retainer 102 and preferably has a bore 142 for receiving the upper end of cylinder 10. Cylinder 10 has a notch or opening 143 communicating with a clearance 144 provided in bore 142 for communication of the space above piston 100 with the interior of housing 5. This relieves any pressure or partial vacuum which might otherwise form above piston 100.

The above being a complete description of an illustrative embodiment of the invention, what is claimed as new and desired to be secured by Letters Patent of the United States is:

1. A hydraulic power lift for a tractor having a support fixed thereon and an implement lifting rockshaft rockably carried by the support, said power lift including a housing and a ram associated therewith and including a piston rod guided for reciprocatory movement in said housing, an oscillatable actuating arm fixed to said rockshaft, extending therefrom and terminating adjacent said piston rod to receive oscillating motion therefrom, a link pivotally supported on the tractor, spaced from said arm in the direction of motion of said piston rod and coextensive with and parallel to said arm, a thrust block pivoted to and carried by said arm and said link in position to receive thrust from said piston rod for oscillating said arm, and friction minimizing contact means between said piston rod and said thrust block.

2. A hydraulic power lift for a tractor having a support fixed thereon and an implement lifting rockshaft rockably carried by the support, said power lift including a housing, a ram reciprocable in said housing and including a piston rod, a guide rod having an axis parallel to the axis of said piston rod and slidably associated with said housing, a head member rigidly secured to said piston rod and to said guide rod so as to resist the transmission of lateral forces to said piston rod, an oscillatable actuating arm fixed to said rockshaft extending therefrom and terminating adjacent said piston rod to receive oscillating motion therefrom, a link pivotally supported on the tractor, spaced from said arm in the direction of motion of said piston rod, coextensive with and parallel to said arm, a thrust block pivoted to and carried by said arm and said link in position to receive thrust from said piston rod by engagement with said head member for oscillating said arm, and friction minimizing contact means between said thrust block and said head member.

3. A hydraulic power lift for a tractor having a support fixed thereon and an implement lifting rockshaft rockably carried by the support, said power lift including a housing, a ram reciprocable in said housing and including a piston rod, a guide rod having an axis parallel to the axis of said piston rod and slidably associated with said housing, a head member rigidly secured to said piston rod and to said guide rod so as to resist the transmission of lateral forces to said piston rod, an oscillatable actuating arm fixed to said rockshaft extending therefrom and terminat-

ing adjacent said piston rod to receive oscillating motion therefrom, a link pivotally supported on the tractor, spaced from said arm in the direction of motion of said piston rod, coextensive with and parallel to said arm, a thrust block pivoted to and carried by said arm and said link in position to receive thrust from said piston rod by engagement with said head member for oscillating said arm, and anti-friction roller contact means between said thrust block and said head member.

4. A hydraulic power lift for a tractor having a support fixed thereon and an implement lifting rockshaft rockably carried by the support, said power lift including a housing, a ram reciprocable in said housing and including a piston rod, a guide rod having an axis parallel to the axis of said piston rod displaced therefrom in a plane normal to said rockshaft and slidably associated with said housing, a head member rigidly secured to said piston rod and to said guide rod so as to resist the transmission of lateral forces to said piston rod, an oscillatable actuating arm fixed to said rockshaft extending therefrom and terminating adjacent said piston rod to receive oscillating motion therefrom, a link pivotally supported on the tractor, spaced from said arm in the direction of motion of said piston rod, coextensive with and parallel to said arm, a thrust block pivoted to and carried by said arm and said link in position to receive thrust from said piston rod by engagement with said head member for oscillating said arm, and friction minimizing contact means between said thrust block and said head member.

5. In a hydraulic power lift for a tractor the combination of a housing mounted on the tractor, a ram associated with the housing and including a piston rod guided for reciprocating movement in said housing, a support fixed on the tractor, an implement lifting rockshaft rockably carried by the support, an arm fixed to said rockshaft, extending therefrom and terminating adjacent said piston rod to receive oscillating motion therefrom, a link pivotally carried by said support, spaced from said arm in the direction of motion of said piston rod and co-extensive with and parallel to said arm, a thrust block pivoted to and carried by said arm and said link in position to receive thrust from said piston rod for oscillating said arm, and friction minimizing contact means between said piston rod and said thrust block.
